ABSTRACT

The drilling rig includes a first substructure and a second substructure. The second substructure is positioned generally parallel to and spaced apart from the first substructure and generally the same height as the first substructure. The drilling rig further includes a drill floor coupled to the first and second substructures, where the drill floor positioned substantially at the top of the first and second substructures.

CROSS-REFERENCE TO RELATED APPLICATIONS

This application is a continuation of U.S. Ser. No. 15/893, 463, which is a continuation of U.S. application Ser. No. 15/191,140, which is a continuation in part which claims priority from U.S. application Ser. No. 14/616,234, filed Feb. 6, 2015, and U.S. application Ser. No. 14/180,049 filed Feb. 13, 2014. U.S. application Ser. No. 14/616,234 is itself a continuation in part of U.S. application Ser. No. 14/180,049, which is itself a non-provisional application which claims priority from U.S. provisional application No. 61/764,259, filed Feb. 13, 2013.

FIELD OF THE DISCLOSURE

The present disclosure relates generally to drilling rigs, and specifically to slingshot rig structures for land drilling in the petroleum exploration and production industry.

BACKGROUND OF THE DISCLOSURE

Land-based drilling rigs may be configured to be traveled from location to location to drill multiple wells within the same area known as a wellsite. In certain situations, it is necessary to travel across an already drilled well for which there is a well-head in place. Further, mast placement on land-drilling rigs may have an effect on drilling activity. For example, depending on mast placement on the drilling rig, an existing well-head may interfere with the location of land-situated equipment such as, for instance, existing well-heads, and may also interfere with raising and lowering of equipment needed for operations.

SUMMARY

The present disclosure provides for a land based drill rig. The land based drill rig may include a first and a second lower box, the lower boxes positioned generally parallel and spaced apart from each other. The land based drill rig may further include a drill rig floor. The drill rig floor may be coupled to the first lower box by a first strut, the first lower box and first strut defining a first substructure. The drill rig floor may also be coupled to the second lower box by a second strut, the second lower box and second strut defining a second substructure. The struts may be hingedly coupled to the drill rig floor and hingedly coupled to the corresponding lower box such that the drill floor may pivot between an upright and a lowered position. The drill rig floor may include a V-door oriented to generally face one of the substructures.

The present disclosure also provides for a land based drilling rig. The land based drilling rig may include a first and a second lower box, the lower boxes positioned generally parallel and spaced apart from each other. The land based drill rig may further include a drill rig floor. The drill rig floor may be coupled to the first lower box by a first strut, the first lower box and first strut defining a first substructure. The drill rig floor may also be coupled to the second lower box by a second strut, the second lower box and second strut defining a second substructure. The struts may be hingedly coupled to the drill rig floor and hingedly coupled to the corresponding lower box such that the drill rig floor may pivot between an upright and a lowered position. The drill

rig floor may include a V-door oriented to generally face one of the substructures. The land based drilling rig may further include a mast coupled to the drill rig floor. The land based drilling rig may further include a tank support structure affixed to the first or second substructure. The tank support structure may include a tank and mud process equipment. The land based drilling rig may further include a grasshopper positioned to carry cabling and lines to the drilling rig. The grasshopper may be positioned to couple to the drill floor generally at a side of the drill rig floor, and the side of the drill rig floor to which the grasshopper couples may face towards the first or second substructure.

BRIEF DESCRIPTION OF THE DRAWINGS

The summary and the detailed description are further understood when read in conjunction with the appended drawings. For the purpose of illustrating the present disclosure, there are shown in the drawings exemplary embodiments of said disclosure; however, the disclosure is not limited to the specific methods, compositions, and devices disclosed. In addition, the drawings are not necessarily drawn to scale. In the drawings:

FIG. 1 is a side elevation from the driller's side of a drilling rig consistent with at least one embodiment of the present disclosure.

FIG. 2 is an overhead view of a drilling rig consistent with at least one embodiment of the present disclosure.

FIG. 3 is a perspective view of a drilling rig consistent with at least one embodiment of the present disclosure.

FIG. 4 is a side elevation of a drilling rig consistent with at least one embodiment of the present disclosure in a mast lowered position.

FIG. 5 is a side elevation view of the drilling rig of FIG. 4 in a mast raised position.

DETAILED DESCRIPTION

The present disclosure may be understood more readily by reference to the following detailed description, taken in connection with the accompanying figures, which form a part of this disclosure. It is to be understood that this disclosure is not limited to the specific devices, methods, applications, conditions or parameters described and/or shown herein, and that the terminology used herein is for the purpose of describing particular embodiments by way of example only and is not intended to be limiting of the present disclosure. Also, as used in the specification, including the appended claims, the singular forms "a," "an," and "the" include the plural, and reference to a particular numerical value includes at least that particular value, unless the context clearly dictates otherwise. The term "plurality," as used herein, means more than one.

FIG. 1 depicts a side elevation of drilling rig 10 from the "driller's side" consistent with at least one embodiment of the present disclosure. Drilling rig 10 may include drill rig floor 20, right substructure 30, and left substructure 40. Right and left substructures 30, 40 may support drill rig floor 20. Mast 50 may be mechanically coupled to one or both of right and left substructures 30, 40 or drill rig floor 20. As would be understood by one having ordinary skill in the art with the benefit of this disclosure, the terms "right" and "left" as used herein are used only to refer to each separate substructure to simplify discussion, and are not intended to limit this disclosure in any way. In some embodiments, drill rig floor 20 may include V-door 23, defining a V-door side of drill rig floor 20 and V-door side 22 of drilling rig 10 may

be located over right substructure 30. The V-door side 52 of mast 50 may correspondingly face right substructure 30. Pipe handler 24 may be positioned to carry piping through a V-door as understood in the art positioned on V-door side 22 of drilling rig 10. In some embodiments, grasshopper 60 may be positioned to carry cabling and lines to drilling rig 10. In other embodiments (not shown), V-door side 22 and mast V-door side may face left substructure 40. In some embodiments, as depicted in FIG. 1, blow out preventer 90 may be located between left substructure 40 and right substructure 30, i.e. drilling rig 10 may be centered over a wellbore.

In some embodiments, tank support structure 80 and tanks 70 may be included in drilling rig 10. Tank support structure 80 may be affixed to right substructure 30 or left substructure 40 by means known to those of ordinary skill in the art with the benefit of this disclosure, including, but not limited to, welding and bolting. As shown in FIG. 1, tank support structure 80 may be affixed to left substructure 40. Tank support structure 80 may be located on the opposite substructure from V-door side 22 of drilling rig 10. Tanks 70 may, for example, be mud tanks, auxiliary mud tanks, or other tanks useful in drilling operations and may be located within tank support structure 80. In some embodiments, mud process equipment 100 may also be mounted within tank support structure 80. Mud process equipment may include, for example, shakers, filters, and other equipment associated with the use of drilling mud.

In some embodiments, tank support structure 80 may be mechanically coupled to right substructure 30 or left substructure 40 by one or more equipment support cantilevers 63. In some embodiments, one or more equipment support cantilevers 63 may be hingedly coupled to one or both of right and left substructures 30, 40. Equipment support cantilevers 63 may be utilized to support one or more pieces of drilling rig equipment mechanically coupled to equipment support cantilevers 63 including, for example and without limitation, tank support structure 80, drill line spooler 65, hydraulic power units (HPUs), compressors, variable frequency drives (VFDs), choke manifolds, accumulators, or other pieces of rig equipment. In some embodiments, one or more of right and left substructures 30, 40 may include one or more compartments 68. Compartments 68 may be formed in an interior of the respective substructure 30, 40. In some embodiments, compartments 68 may be closed by hatch or door 69, which may close compartments 68 while allowing access thereto.

In some embodiments, one or both of right and left substructures 30, 40 may include one or more upper equipment support cantilevers 67. As depicted in FIG. 1, each upper equipment support cantilever 67 may be hingedly coupled to one of right or left substructure 30, 40. In some embodiments, upper equipment support cantilevers 67 may be utilized to support one or more pieces of drilling rig equipment mechanically coupled to upper equipment support cantilevers 67, including one or more of, for example and without limitation, mud process equipment 100, choke manifold 102, accumulator 104, mud gas separators, process tanks, trip tanks, drill line spoolers, HPU's, VFD, or driller's cabin 106.

FIG. 2 depicts an overhead view of drilling rig 10 consistent with at least one embodiment of the present disclosure in which V-door side 22 of drilling rig 10, drill rig floor 20, and tank support structure 80 are shown. In some embodiments, choke manifold 102 may likewise be located on the rig floor. In some embodiments, accumulator 104 may likewise be located on the rig floor.

In some embodiments, substructures 30, 40 may be fixed as depicted in FIGS. 1, 2. In some embodiments, as depicted in FIG. 3, substructures 30', 40', may pivotably support drill rig floor 20. Drill rig floor 20 may be pivotably coupled to one or more lower boxes 130 by a plurality of struts 140 together forming substructures 30', 40' (pivot points shown as pivot points 141). Lower boxes 130 may support drill rig floor 20. Lower boxes 130 may be generally parallel to each other and spaced apart. Struts 140 may be hingedly coupled to drill rig floor 20 and to lower boxes 130. In some embodiments, struts 140 may be coupled to lower boxes 130 and drill rig floor 20 such that they form a bar linkage therebetween, allowing relative motion of drill rig floor 20 relative to lower boxes 130 while maintaining drill rig floor 20 parallel to lower boxes 130. Thus, drill rig floor 20 may be moved from an upper position as shown in FIG. 3 to a lower position while remaining generally horizontal.

In some embodiments, the movement of drill rig floor 20 may be driven by one or more hydraulic cylinders 150. In some embodiments, when in the upright position, one or more diagonals 160 may be coupled between drill rig floor 20 and lower boxes 130 to, for example and without limitation, maintain drill rig floor 20 in the upright position.

In some embodiments, with reference to FIGS. 1-3, as they are mounted directly to a substructure (30 or 40) of drilling rig 10, one or more pieces of equipment may travel with drilling rig 10 during a skidding operation. For example and without limitation, equipment may include tanks 70, mud process equipment 100, choke manifold 102, accumulator 104, mud gas separators, process tanks, trip tanks, drill line spoolers, HPU's, VFD, or driller's cabin 106. As such any pipe or tubing connections between or taken from tanks 70, mud process equipment 100, choke manifold 102, and/or accumulator 104 may remain connected during the skidding operations. This arrangement may allow, for example, more rapid rig disassembly ("rigging-down") and assembly (or "rigging-up") of drilling rig 10 before and after a skidding operation.

Additionally, by facing V-door side 22 of drilling rig 10 toward one of the substructures 30, 40, equipment and structures that pass through the V-door 23 or to drill rig floor 20 from V-door side 22 of drilling rig 10 may, for example, be less likely to interfere with additional wells in the well field.

In some embodiments, as depicted in FIGS. 4, 5, mast 50 may be mechanically coupled to rig drill rig floor 20. In some embodiments, not depicted, mast 50 may be mechanically coupled to one or both of right and left substructures 30, 40. In some embodiments, mast 50 may be mechanically coupled to drill rig floor 20 by one or more pivot points 54. In some embodiments, as depicted in FIG. 4, mast 50 may be mechanically coupled to pivot points 54 in a horizontal position, defined as a mast lowered position of drilling rig 10. In some embodiments, mast 50 may be transported in the horizontal position. In some embodiments, mast 50 may be constructed from one or more mast subunits and may be transported in a disassembled state. In some embodiments, drilling rig 10 may include one or more hydraulic cylinders 56. Hydraulic cylinders 56 may, in some embodiments, be mechanically coupled to one of drill rig floor 20 or one or both of right and left substructures 30, 40. Hydraulic cylinders 56 may be mechanically coupled to mast 50 at one or more mast lift points 58. Once hydraulic cylinders 56 are mechanically coupled to mast 50, hydraulic cylinders 56 may be extended to raise mast 50 from the horizontal position depicted in FIG. 4 a vertical position as depicted in FIG. 5, defined as a mast raised position of drilling rig 10.

In some embodiments, hydraulic cylinders 56 may be mechanically coupled to drill rig floor 20 at one or more rig floor lifting points 21.

In some embodiments, as depicted in FIGS. 4, 5, drilling rig 10 may include one or more hydraulic walkers 120. Hydraulic walkers 120 may, in some embodiments, be positioned at a lower end of one or both right and left substructures 30, 40. In some embodiments, hydraulic walkers 120 may be hydraulically actuatable to move or walk drilling rig 10 to a different location in the wellsite. In some embodiments, hydraulic walkers 120 may be operable to move or walk drilling rig 10 in any direction. In some embodiments, equipment positioned on equipment support cantilevers 63 and upper equipment support cantilevers 67 as previously discussed may be moved with drilling rig 10 as it is moved or walked.

One having ordinary skill in the art with the benefit of this disclosure will understand that the specific configurations depicted in FIGS. 1-5 may be varied without deviating from the scope of this disclosure.

Those skilled in the art will appreciate that numerous changes and modifications can be made to the preferred embodiments of the present disclosure and that such changes and modifications can be made without departing from the spirit of said disclosure. It is, therefore, intended that the appended claims cover all such equivalent variations as fall within the true spirit and scope of said disclosure.

What is claimed is:

1. A slingshot land-based drilling rig comprising:
  - a first substructure having a long axis;
  - a second substructure having a long axis, the long axis of the second substructure generally parallel to the long axis of the first substructure;
  - a drill rig floor coupled to the first and second substructures, the drill rig floor including a V-door, the V-door perpendicular to the long axis of the first substructure;
  - a mast, the mast mechanically coupled to one or more of the first substructure, the second substructure, and the drill rig floor; and
  - a mast hydraulic cylinder mechanically coupled to one of the first substructure, the second substructure, or the drill rig floor and mechanically coupled to the mast; wherein the first elongated substructure and second elongated substructure are adapted to be traveled through a wellsite when coupled to the drill rig floor and assembled and set up for drilling, the mast coupled to the first substructure, the second substructure or the drill rig floor.
2. The land-based drilling rig of claim 1, wherein the first and second substructures comprise:
  - a lower box, the lower box of the first substructure and the lower box of the second substructure positioned generally parallel and spaced apart from each other; and
  - at least one strut, the at least one strut pivotably coupling the drill rig floor to the lower box, the at least one strut hingedly coupled to the drill rig floor and the lower box;
3. The land-based drilling rig of claim 2, wherein the at least one strut is coupled to the lower box and drill rig floor to form a bar linkage.
4. The land-based drilling rig of claim 2, wherein the land-based drilling rig further comprises a raising hydraulic cylinder, the raising hydraulic cylinder mounted on the lower box and the drill rig floor.

5. The land-based drilling rig of claim 1 further comprising one or more hydraulic walkers, the hydraulic walkers positioned at a lower end of one or both of the first and second substructures.

6. The land-based drilling rig of claim 1 further comprising equipment positioned on the land-based drilling rig, wherein the equipment comprises tanks, mud process equipment, choke manifold, accumulator mud gas separator, process tank, trip tank, drill line spooler, VFD, driller's cabin, or a combination thereof.

7. The land-based drilling rig of claim 6, wherein piping or tubing connections between or from tanks, mud processing equipment, choke manifold, accumulator or a combination thereof remain connected while moving the land-based drilling rig.

8. The land-based drilling rig of claim 6, wherein the choke manifold is positioned on the drill rig floor.

9. The land-based drilling rig of 1, wherein an accumulator is positioned on the drill rig floor.

10. The land-based drilling rig of claim 1, wherein the drill rig floor is fixedly coupled to the first and second substructures wherein the drill rig floor is immovable with respect to the first and second substructures when the land-based drilling rig is assembled and set up for drilling.

11. The land-based drilling rig of claim 1, wherein the land-based drilling rig is a box-on-box rig.

12. The land-based drilling rig of claim 1, wherein the land-based drilling rig comprises only two substructures.

13. The land-based drilling rig of claim 1, wherein the mast has a V-door side and wherein the V-door side of the mast is perpendicular to a long axis of the first substructure.

14. A method comprising:
transporting a slingshot land-based drilling rig to a well field and positioning the land-based drilling rig, wherein the land-based drilling rig comprises:

a first substructure having a long axis;
a second substructure having a long axis, the long axis of the second substructure generally parallel to the long axis of the first substructure;

a drill rig floor coupled to the first and second substructures, the drill rig floor including a V-door, the V-door perpendicular to the long axis of the first substructure, the drill rig floor having a V-door side on which the V-door is located;

a mast, the mast mechanically coupled to one or more of the first substructure, the second substructure, and the drill rig floor, the mast having an open side, the open side facing the V-door side; and

a mast hydraulic cylinder mechanically coupled to one of the first substructure, the second substructure, or the drill rig floor and mechanically coupled to the mast; positioning the mast in a horizontal position; raising the mast from a horizontal to a vertical position; and

traveling the first elongated substructure and second elongated substructure through a wellsite, wherein the first elongated substructure and second elongated substructure are traveled through a wellsite when coupled to the drill rig floor, and assembled and set up for drilling, the mast coupled to the first substructure, and the second substructure or the drill rig floor.

15. The method of claim 14, wherein the first and second substructures comprise:

a lower box, the lower box of the first substructure and the lower box of the second substructure positioned generally parallel and spaced apart from each other; and

at least one strut, the at least one strut pivotably coupling the drill rig floor to the lower box, the at least one strut hingedly coupled to the drill rig floor and the lower box;

wherein the drill rig floor is immovable with respect to the first and second substructures when the land-based drilling rig is assembled and set up for drilling.

16. The method of claim 15 further comprising the step of: raising the drill rig floor from a lowered position to an upright position while maintaining the drill rig floor parallel to the lower boxes.

17. The method of claim 16, wherein the step of raising the drill rig floor from a lowered position to a vertical position is performed with the drill rig floor maintained in a horizontal position.

18. The method of claim 16 further comprising after the step of raising the drill rig floor:

coupling one or more diagonals between the drill rig floor and the lower boxes.

19. A slingshot land-based drilling rig comprising:

a first substructure;

a second substructure, the second substructure being positioned generally parallel to the first substructure, a space between the first and second substructures having a long axis;

a drill rig floor coupled to the first and second substructures, the drill rig floor including a V-door, the V-door perpendicular to the long axis of the space between the first and second substructures;

a mast, the mast mechanically coupled to one or more of the first substructure, the second substructure, and the drill rig floor; and

a mast hydraulic cylinder mechanically coupled to one of the first substructure, the second substructure, or the drill rig floor and mechanically coupled to the mast

wherein the first elongated substructure and second elongated substructure are adapted to be traveled through a wellsite when coupled to the drill rig floor, the mast coupled to the first substructure, the second substructure or the drill rig floor and the mast hydraulic cylinder mechanically coupled to the first substructure, the second substructure or the drill floor.

20. The land-based drilling rig of claim 19, wherein the first and second substructures comprise:

a lower box, the lower box of the first substructure and the lower box of the second substructure positioned generally parallel and spaced apart from each other; and at least one strut, the at least one strut pivotably coupling the drill rig floor to the lower box, the at least one strut hingedly coupled to the drill rig floor and the lower box;

wherein the drill rig floor is immovable with respect to the first and second substructures when the land-based drilling rig is assembled and set up for drilling.

21. The land-based drilling rig of claim 20, wherein the at least one strut is coupled to the lower box and drill rig floor to form a bar linkage.

22. The land-based drilling rig of claim 20, wherein the land-based drilling rig further comprises a raising hydraulic cylinder, the raising hydraulic cylinder mounted on the lower box and the drill rig floor.

23. The land-based drilling rig of claim 19, wherein the drill rig floor is fixedly coupled to the first and second substructures wherein the drill rig floor is immovable with respect to the first and second substructures when the land-based drilling rig is assembled and set up for drilling.

24. The land-based drilling rig of claim 19, wherein the land-based drilling rig is a box-on-box rig.

25. A slingshot land-based drilling rig comprising:

a first substructure having a long axis;

a second substructure having a long axis, the long axis of the second substructure generally parallel to the long axis of the first substructure;

a drill rig floor coupled to the first and second substructures, the drill rig floor including a V-door, the V-door perpendicular to the long axis of the first substructure, the drill rig floor having a V-door side on which the V-door is located;

a mast, the mast mechanically coupled to one or more of the first substructure, the second substructure, and the drill rig floor, the mast having an open side, the open side facing the V-door side; and

a mast hydraulic cylinder mechanically coupled to the drill rig floor and mechanically coupled to the mast.

26. The land-based drilling rig of claim 25, wherein the first and second substructures comprise:

a lower box, the lower box of the first substructure and the lower box of the second substructure positioned generally parallel and spaced apart from each other; and at least one strut, the at least one strut pivotably coupling the drill rig floor to the lower box, the at least one strut hingedly coupled to the drill rig floor and the lower box;

wherein the drill rig floor is immovable with respect to the first and second substructures when the land-based drilling rig is assembled and set up for drilling.

27. The land-based drilling rig of claim 26, wherein the land-based drilling rig further comprises a raising hydraulic cylinder, the raising hydraulic cylinder mounted on the lower box and the drill rig floor.

28. The land-based drilling rig of claim 25, wherein the drill rig floor is fixedly coupled to the first and second substructures wherein the drill rig floor is immovable with respect to the first and second substructures when the land-based drilling rig is assembled and set up for drilling.

29. The land-based drilling rig of claim 25, wherein the land-based drilling rig is a box-on-box rig.
